UNITED STATES PATENT OFFICE.

JAMES BANWELL, OF CLEVELAND, OHIO, ASSIGNOR OF ONE-THIRD TO ROBERT L. BECK,
OF CLEVELAND, OHIO.

STREET-PAVING.

1,078,982.

Specification of Letters Patent.

Patented Nov. 18, 1913.

Application filed May 13, 1912. Serial No. 696,880.

To all whom it may concern:

Be it known that I, JAMES BANWELL, citizen of the United States, residing at Cleveland, in the county of Cuyahoga and State 5 of Ohio, have invented certain new and useful Improvements in Street-Paving, of which the following is a specification.

This invention pertains to an improvement in street paving, and consists in a pressure absorbing strip adapted to be interposed between the pavement proper and the curbing to relieve pressure when the pavement expands under the influence of heat, all as shown and described and particularly 10 15 pointed out in the claims.

In the accompanying drawings Figure 1 is a perspective view of a section of pavement and curbing embodying my invention between the same, and Fig. 2 is a perspective 20 view of one of the cushioning strips or pieces representing the invention in one of its possible forms.

As above indicated, the invention involves an expandible cushioning device for paved 25 streets.

It is well known that where suitable stone or equivalent curbing is used along with brick or stone or equivalent pavement there always is a tendency for the pavement to 30 swell or bulge at some point or other to accommodate the natural expansion and which is liable to be considerable, especially on hot summer days, and which can not find relief at the curbing. Various unsatisfactory 35 attempts have been made to overcome or avoid this condition and which is inevitable if the blocks or bricks are built compactly against the curb stone. I have therefore invented the strip herein shown and which for the 40 present and preferably has a fairly solid body *b* wholly or mostly of asphalt and containing a suitable core *c* which may be of wire fabric or wire strips or pieces embedded therein or the equivalent of these, 45 the idea being to make a strip which in itself is more or less flexible at all times and adapted to be fairly rigid for handling and which will give character and quality to the strip which it can not possess without some

such internal and sustaining portion. Of course the said reinforcement need not necessarily be of metal but in any event it must have sustaining value for the asphalt or body portion of the strip, and the said strip is shown as having the same depth as the 55 paving block or brick and say an inch or so in thickness and placed next to the curb *d*. The length of the said strip or piece is not really material but a length proportioned as shown gives very good satisfaction and 60 the said strip of course becomes a permanent portion of the pavement. The opposite ends of the strip are beveled or tapered to provide angular faces *e* in the same parallel planes so that overlapping joints may be 65 obtained in laying the strips end to end. The strips are flexible to admit of their use on short curves, as at street corners, and are sold as separate articles of manufacture and use. Their use saves time, labor and expense in the laying of street paving, as well 70 as having the advantages hereinbefore set forth.

What I claim is:

1. As a new article of manufacture and 75 sale, a street paving strip adapted to be interposed between the curbing and paving blocks, the same consisting of asphalt molded to the desired shape and size and having a flexible reinforcing metallic core. 80

2. As a new article of manufacture and sale, a flat sided strip of flexible asphalt adapted to be used between the curb and the paving and having a flexible metallic core and oppositely beveled ends adapted to overlap the ends of adjacent strips. 85

3. A preformed expansion joint strip comprising an elongated strip of asphalt or equivalent material of substantial thickness provided with a flexible reinforcement em- 90 bedded therein.

In testimony whereof I affix my signature in presence of two witnesses.

JAMES BANWELL.
